UNITED STATES PATENT OFFICE.

GUY R. POORMAN, OF SHERWOOD, OHIO.

DISPLAY CASE.

1,411,890.

Specification of Letters Patent.

Patented Apr. 4, 1922.

Application filed September 15, 1920. Serial No. 410,378.

To all whom it may concern:

Be it known that I, GUY R. POORMAN, a resident of Sherwood, county of Defiance, and State of Ohio, have made an Invention 5 Appertaining to Display Cases; and I do hereby declare the following to be a full, clear, and exact description of the invention, such as will enable others skilled in the art to which it appertains to make and use the 10 same, reference being had to the accompanying drawings, and to the characters of reference marked thereon, which form a part of this specification.

This invention relates to a commodity display case, and has for its object the provision of a simple and efficient device of this character, the use of which in grocery and other stores for displaying the commodities handled, or a large part thereof, makes it 15 possible to reduce the number of employees, the size of store room and number of display shelves otherwise necessary, and also reduces to a minimum the possibility of shop lifting, dishonesty of employees and of customers taking the wrong basket of merchandise.

The use of the invention also facilitates shopping, as the commodities are all displayed in convenient manner with the prices 20 affixed thereto.

The invention is fully described in the following specification, and while, in its broader aspect, it is capable of embodiment in numerous forms, a preferred embodiment 25 thereof is illustrated in the accompanying drawings, in which,—

Figure 1 is a perspective view of a display case embodying the invention. Fig. 2 is a longitudinal vertical section thereof, 30 with a portion broken away, and Fig. 3 is a view of one of the cross bumpers and price tag display members.

Referring to the drawings, 1 designates a display case or bin of rectangular form 35 provided with or without a bottom and having its top open and preferably inclined from front to rear. The front and rear sides are each provided at their inner sides with vertical grooves 2 for receiving the respective ends of partition boards or members 3, the grooves being of greater number than the stalls to enable the width of the different stalls to be formed thereby to be varied to suit the width of the commodities to be 45 displayed as hereinafter described.

The partitions 3, as well as the ends of the

display case, are provided with a plurality of sets of vertically spaced holes 4 for receiving pins 5 adapted to support ledge strips 6 in desired vertical position on the 60 side walls of the different stalls for supporting articles in desired position in the stalls. For instance, if canned or packaged goods are to be displayed the stalls are made of a width to suit the width of the goods by 65 an adjustment of the partitions 3 and the ledge strips 6 are positioned to engage and support the goods at desired elevation in the respective stalls, care being taken to place goods of substantially the same size or width 70 in the same display stalls. The top edges of the partitions 3 and also of the ends of the display case are provided with sockets 7 for receiving the downwardly bent ends of cross bumper members 8, which are adapted 75 to space the goods of different kinds and also to serve as price card holders. For this purpose the bumpers are preferably made of wire formed in U-shape and provided at its center with an outwardly offset 80 portion 9 for holding a price card. In addition to separating the goods these bumpers also serve to prevent the goods from sliding forward in the stalls should an article be removed from any stall in advance of 85 some of the goods displayed. The bumpers 8 are made of various lengths to suit the width of the stalls.

Some of these stalls may receive trays 10 having a plurality of partitions therein 90 forming the various compartments for holding small quantities of bulk goods, such for instance, as tea, coffee, rice, or the like. These trays are in length preferably coextensive with the length of the stalls, and 95 have their upper side edges provided with outwardly offset flanges 11 for resting on the top edges of the partitions. The flanges 11 are shaped to form internal recesses for receiving the respective edges of the glass 100 covers 12 for the different trays, the covers being slid into place in the tray tops.

The case is preferably provided at its upper rear edge with a rearwardly projecting shelf 13 for displaying some articles, 105 the rear edge of the shelf being provided with an upwardly rising backboard 14. If the shelf is extended at its forward end over the rear portion of the case, such extending portion is preferably made in a separate 110 piece, as shown by the strip 15, and hinged to the shelf 13 to be turned back thereon.

so as to completely uncover the top of the case when desired.

It is evident that the case may be of any size to accomodate the various articles to be displayed or a number of cases may be used for such purpose, and that when one of each article carried in stock is displayed in the case or cases it enables a purchaser to determine more quickly what he wants and the 10 prices of the same without asking questions, and also enables a single person to preside over the case for taking orders. When the orders are taken they may be passed to a stock clerk and filled with goods from the 15 stock room, the goods being taken in most cases from their original shipping cases,

thereby saving the time and labor incident to unpacking the goods and placing them on the shelves preparatory for a purchase, as is customarily done.

Having thus described my invention, what I claim as new and desire to secure by Letters Patent, is,—

A display case having partitions forming a plurality of stalls with the tops of the 25 partitions provided with holes, and wire members adapted to span the stalls and having end portions for removably projecting into holes of adjacent partitions.

In testimony whereof I have hereunto sub- 30 scribed my name to this specification.

GUY R. POORMAN.
